UNITED STATES PATENT OFFICE.

FOYDICE C. BROWN, OF SELMA, CALIFORNIA.

LOCK.

Application filed October 31, 1921. Serial No. 511,790.

To all whom it may concern:

Be it known that I, FOYDICE C. BROWN, a citizen of the United States, residing at Selma, in the county of Fresno and State 5 of California, have invented new and useful Improvements in Locks, of which the following is a specification.

My present invention has reference to a lock for freight car doors.

10 My primary object is to simplify and improve the existing art by producing a locking means between a sliding door and the jamb therefor which will be automatically effected by the movement of the door against 15 the jamb, and in which suitable sealing means is provided for the locking means.

It is a further object to produce a locking means between a sliding door, such as the door of a freight car, and the jamb therefor which shall be of an extremely simple 20 construction, cheaply manufactured, readily applied, automatic in action when the door is moved against the jamb, and which shall be positive in such action.

25 It is a still further object to produce a locking means which is especially designed for latching a slideable car door to the jamb therefor, in which a right angular plate comprising a lock casing, is secured to the 30 end and to the side of the door, said plate having the face thereof secured to the end of the door provided with a round opening and having pivoted on its inner face a flat tumbler which is substantially rounded in 35 plan and which, incident to the weight thereof has one of its ends, which is slotted, projected through the side plate of the lock casing and its body portion partly projected into the opening in the face plate of the casing, 40 while on the door jamb there is swiveled a member having a conical head which is designed, when the door is moved against the jamb to contact with the tumbler to swing the same in the casing and thereafter 45 permit of the tumbler gravitating into engagement with the head, and the lower and slotted end of the said tumbler passing through the referred to slot or opening in the side plate of the casing for the reception 50 of a suitable seal.

The foregoing, and other objects which will appear as the nature of the invention is better understood, may be accomplished by a construction, combination and operative association of parts, such as is disclosed by 55

the drawings which accompany and which form part of this specification.

In the drawings:—

Figure 1 is an elevation of a portion of a 60 slideable door showing the same in contact- ing engagement with its jamb and having thereon a lock in accordance with this in- vention.

Figure 2 is a sectional view, on an en- 65 larged scale, and approximately on the line 2—2 of Figure 1.

Figure 3 is a sectional view on the line 3—3 of Figure 1.

Figure 4 is a view looking toward the 70 edge of the door with the lock thereon.

Figure 5 is a perspective view of the lock 75 casing showing the arrangement of the pivoted tumbler therein.

Figure 6 is a perspective view of the tum- 75 bler.

Figure 7 is a similar view of the swiveled head member or bolt.

Referring now to the drawings in detail, the numeral 1 designates a portion of a car, 80 2 the slideable door which normally covers the opening in the side thereof and which is mounted on suitable tracks, and 3 the jamb against which one end of the door abuts when the door is closed.

In carrying out my invention I provide 85 the jamb 3 with a transverse opening 4, the edges or faces of the jamb being pro- 90 vided with preferably rectangular sockets 5 that communicate with the opening 4. Through the opening there is passed a bolt 95

6. The bolt, in the present instance, has its head formed on its opposed sides with parallel extensions 7 that terminate in in- 95 wardly directed flanges 8, the said flanges being received in a groove 9 in the cross 100 sectionally rounded shank 10 in the bolt member of the improvement. The head 11 of the bolt is, of course, enlarged with re- 105 spect to the thickness of its shank and the outer face of the head 11 is cone-shaped. The head projects through the socket on the inner face of the jamb, and screwed on the bolt there is a nut 12 that is in contact- 110 ing engagement with the inner wall of the said socket. The opposite end of the bolt 105

is also engaged by a nut 13 which is re- 110 ceived in the socket on the end or face of the jamb opposite the just referred to socket. The nut 13, of course, contacting with the inner wall of the last mentioned socket 5. 110

The construction is such that the bolt is supported on the jamb, and because of its shank being received in the socket 5 is permitted a limited swinging movement in any direction, the weighted head of the bolt normally holding the same at a downward angle.

The casing of the lock comprises a right angular plate, the portion thereof which is secured to the edge of the door 2 confronting the jamb will, for the sake of convenience be referred to as the face plate and is indicated by the numeral 14, while the opposite angle plate, which is arranged on and secured to the outer face of the door will hereinafter be referred to as the side plate and is indicated by the numeral 15. The edge of the door on which the face plate is arranged is provided with a depression 16, the said depression being less than the length of the face plate, that is, when the face plate is projected beyond the edge of the door for the thickness thereof. It is, of course, to be understood that both the face and side plates of the lock casing will be let in the door. The means for securing the face plate to the edge of the door are preferably in the nature of lag screws 17, the means for securing the side plate to the side of the door being preferably in the nature of a bolt 18 that passes through a suitable opening in the preferably outer and reduced end of the said side plate and through the door. This bolt is engaged by a nut 19 that is let into a socket on the inner face of the door, and suitable means, broadly indicated by the numeral 20, are provided for holding the bolt 18 and the nut 19 against turning. The means 20 are not essential even should the bolt 18 be removed, when the door is closed, the lock cannot be tampered with without inflicting perceptible damage to the casing and without breaking the seal which engages the weighted tumbler which is presently to be described.

The face plate 14 of the lock casing is provided with a round opening 21 which is arranged in a line with the conical head 11 of the bolt so that the bolt will be received through the said opening and into the referred to depression in the end of the door, when the door is moved on its tracks against the jamb.

Pivotedly secured, as at 22, adjacent to the upper and outer corner of the face plate 14, but on the inner face of the said face plate is the tumbler 23. The tumbler comprises a flat metallic member which is substantially semi-cylindrical in plan. For distinction, the pivoted end of the tumbler is indicated by the numeral 24, and the same may have arranged upon its inner edge, or the edge thereof opposite that which partly covers the opening 21 which may be

in the path of contact with the upper securing elements for the face plate for limiting the inward swinging of the tumbler in the lock casing. The opposite or lower portion of the tumbler is gradually widened, 70 as at 25, and from thence reduced to provide an extension 26 that passes through an opening 27 in the side plate 15, at its juncture with the face plate 14 of the lock casing. The extension is slotted, as at 28. The 75 widened lower end of the tumbler, together with its extension, and also incident to the manner in which the tumbler is pivotally secured to the lock casing is influenced by the weight thereof, so that the slot 28 has 80 its inner wall in a line with the outer face of the side plate 15 when the tumbler is in bolt engaging position. The inner edge of the upper portion 24 of the tumbler is preferably bowed outwardly from its pivot 85 to the rounded central portion of the said tumbler, and the lower part of this bowed portion is normally received opposite the upper portion of the rounded opening 21. The central and inner edge of the tumbler 90 may be substantially straight, as indicated by the numeral 29, and this edge is also normally positioned to partly close the opening 21. The outward swinging of the lock through its casing is limited by the contact 95 of the shoulders thereon with the inner face of the side plate 15 of the casing.

From the foregoing, it will be apparent that when the door is slid to bring its end against the jamb, the headed end of the 100 swiveled bolt will be guided through the opening 21 in the lock casing, the conical end of the said bolt influencing the tumbler to swing the same inwardly of the lock casing and when the rear face or shoulder of 105 the head of the bolt enters the depression, the tumbler will gravitate so that its inner edge will engage with the shoulder on the inner face of the head of the bolt and in this manner the door is automatically latched 110 to the jamb. Of course, the door cannot be moved to open position until a pressure is exerted upon the projecting end 26 thereof to force the tumbler inwardly of the casing. Also by swivelling the bolt and pivotally 115 supporting the tumbler, the door cannot be released from the jamb by any shocks or jars to which the car may be subjected. However, to positively hold the tumbler in locking position, when the car is enroute, I pass 120 through the slot 28 in the outer end or extension 27 of the tumbler 23 a seal 29 of the ordinary character employed on railways.

It is thought that the foregoing description, when taken in connection with the 125 drawings will fully set forth the construction, operation and advantages of the improvement, but it is also thought necessary to add that the nature of the invention is such as to permit of the employment of modifica- 130

tions in the construction and arrangement of the several parts thereof and consequently I am not to be limited to the precise construction shown and described, but am entitled to all such departures therefrom as fall within the scope of what is claimed.

Having described the invention, I claim:—

1. In combination with a sliding door and a jamb therefor, of a bolt member including a shank having an enlarged outer cone-shaped head and said shank being connected to the jamb, a pivotally supported tumbler on the edge of the door opposite the jamb, said tumbler comprising a flat member which is arched in plan and which has its inner edge in the path of contact with the conical head of the bolt and designed to be engaged thereby, when the door is moved against the jamb, and by virtue of such engagement to move off of the head and to engage the shank of the bolt directly to the rear of the head, and means for limiting the swinging of the tumbler in two directions.
2. In combination with a sliding door and a jamb therefor, of a swiveled bolt having

an outwardly projecting cone-shaped head on the jamb, a lock casing comprising a right angular plate secured to the edge of the door next the jamb and to the side of the door, 30 said casing having a round opening therethrough in a line with the head of the bolt and designed to receive the head therethrough when the door is moved against the jamb, a tumbler having a lower weighted end 35 pivoted in the casing and comprising a flat member which is substantially round in plan and which has its lower free end weighted whereby said tumbler will swing to cause its inner edge to be partly projected into the 40 bolt opening in the lock casing to arrange the same in the path of contact with the head of the bolt, means limiting the swinging of the tumbler in this direction, means 45 limiting the swinging of the tumbler in an opposite direction, and the lower end of the tumbler having a slotted extension passing through an opening in the side plate of the lock casing.

In testimony whereof I affix my signature. 50

FOYDICE C. BROWN.
